UNITED STATES PATENT OFFICE.

ADOLPH E. ERICKSON, OF ROCKFORD, ILLINOIS.

SACK.

1,234,318.

Specification of Letters Patent. Patented July 24, 1917.

Application filed March 16, 1915. Serial No. 14,802.

To all whom it may concern:

Be it known that I, ADOLPH ERICKSON, a citizen of the United States, residing at Rockford, in the county of Winnebago 5 and State of Illinois, have invented certain new and useful Improvements in Sacks, of which the following is a specification.

My invention relates to new and useful improvements in sacks or bags and more 10 particularly to a bag or sack of this character adapted for holding potatoes, sugar, or various other similar articles.

The primary object of the invention is the provision of a device of this character having suitable handholds whereby it may be 15 more readily handled.

It is a well known fact that when sacks or bags are filled with various types of material that it is hard to secure a handhold 20 thereon and some difficulty is experienced in raising them. It is to overcome these objections that my sack or bag is designed and I have provided such a sack or bag which is simple and inexpensive in construction and which would add little if any 25 expense to the bags or sacks as now commonly constructed.

With these and other objects in view the invention consists in the novel details of 30 construction and arrangement of parts which will be more clearly understood from the following description and drawings, in which,

Figure 1 is a perspective view showing the 35 manner in which the sack or bag may be grasped.

Fig. 2 is a fragmental face view.

Fig. 3 is a vertical section on the line 3-3 of Fig. 2, looking in the direction of 40 the arrow.

In the drawings, the numeral 1 indicates the body portion of the bag which is of usual construction and which when not filled will be open at the top and when filled may 45 be closed in any suitable manner but preferably by tying in such a manner as to form ears or loops, as indicated at 2 in Fig. 1 of the drawings.

On the bottom of the bag, and formed in-

tegral therewith, are extensions 3 which are 50 adapted to be used for handholds in lifting the bags or sacks and are made to project from the bottom perpendicularly thereto, the outer edges of the extensions being in line with the side edges of the sack. As 55 stated, these projections or handholds are made integral with the body portion of the bag and, as shown in Fig. 3 of the drawings, are preferably open or in other words communicate with the body portion of the 60 sack or bag. These projections or handholds 3 have the inturned seams 4, as clearly shown in Fig. 3 of the drawings. It will be understood that in constructing 65 the bag all the seams are formed on the interior thereof thereby making the bag neat in appearance on the outside.

The sack or bag is preferably formed of a single piece of material which is folded so as to form a seam on one side thereof and 70 at the bottom, the extensions or handholds being formed by folding the bottom, as indicated in the drawings.

Having fully described the detail construction of my device it is thought that the 75 advantages will be readily understood. In lifting the bag it may be grasped as indicated in Fig. 1 of the drawings, and the person lifting the same can secure a good hold thereon. As shown in the preferred 80 form of the invention the material in the bag will also enter the extensions or handholds 3 thereby stiffening the same and forming a good secure grip.

Having fully described my invention 85 what I claim as new and desire to secure by Letters Patent is:—

1. A sack of textile material comprising a body having two projecting portions on the bottom thereof integral with the body 90 and extending parallel to the major axis of the sack, said projecting portions forming handholds and communicating with the interior of the sack.

2. A sack of textile material comprising a 95 body open at the top to the full dimension of the sack and a projecting portion extending from each bottom corner of the sack

parallel to the major axis thereof and opening into the sack, said projections being of cylindrical form and of a size to form hand-holds for gripping the bottom of the sack to empty the contents thereof, the outer peripheries of said projections being in line with the sides of the sack body.

Copies of this patent may be obtained for five cents each, by addressing the "Commissioner of Patents, Washington, D. C."

In testimony whereof I affix my signature in presence of two witnesses.

ADOLPH E. ERICKSON.
